Primary Examiner — Kevin K Rudzinski(74) Attorney, Agent, or Firm — Lambert Shortell & Connaughton; David J. Connaughton, Jr.(57) CLAIM

The ornamental design for a race shirt pockets, as shown and described.

DESCRIPTION

FIG. 1 is an isometric view of the race shirt pockets, which embodies my design;

FIG. 2 is a top plan view thereof;

FIG. 3 is a bottom plan view thereof;

FIG. 4 is a side view thereof;

FIG. 5 is a side view thereof;

FIG. 6 is a side view thereof;

FIG. 7 is a side view thereof; and,

FIG. 8 is a front view thereof.

The broken lines shirt in FIG. 8 shows the invention in a position of use and illustrates environmental subject matter that forms no part of the claimed design.

1 Claim, 4 Drawing Sheets(56)
